CLAIM

I claim the ornamental design for a bracelet, as shown and described.

DESCRIPTION

FIG. 1 is a perspective view of a bracelet, showing my new design in a worn configuration;

FIG. 2 is a perspective view thereof, illustrated in a flat configuration;

FIG. 3 is a perspective view thereof, illustrated with a slit of the design slightly open;

FIG. 4 is a top plan view of FIG. 2;

FIG. 5 is a front elevational view of FIG. 2;

FIG. 6 is a bottom plan view of FIG. 2; and,

FIG. 7 is a left-side elevational view of FIG. 2, the right-side elevational view being a mirror image thereof.

The broken lines showing a person in FIG. 1 and text in FIGS. 1-4 depict environmental matter and form no part of the claimed design. The shading on the inside edge of the first aperture of the bracelet depicts the color red, and the shading on the remaining inside edges of the other apertures and slit depicts the color black.
